PAPER BAG

Donald E. Woodward, Middletown, Ohio, assignor
to The Raymond Bag Company, Middletown,
Ohio, a corporation of Ohio

Application April 14, 1932. Serial No. 605,244

12 Claims. (Cl. 229—55)

This invention relates to paper bags and more particularly to multi-wall bags having pasted end closures.

Paper bags are extensively used for packing and shipping heavy materials, such as cement, lime and the like, and in order to secure the necessary strength and flexibility it is customary to provide bags the walls of which consist of a plurality of plies of paper. Usually the bags are formed by folding a series of webs of paper one about the other, with the edges of each web overlapped and pasted, to form a continuous multi-ply tube which is then cut to bag lengths. In the pasted type of bag one or both ends of the bag are closed by folding inwardly the end portions of the multi-ply walls to form flaps, which flaps are pasted one to the other. In the case of a multi-ply bag it is necessary that the several plies of the longer or side flaps should be pasted one to the other. Consequently each flap consists of the several plies of paper and of a corresponding number of layers of paste and this results in a heavy relatively stiff flap and it is difficult to so paste such a stiff heavy flap to an adjacent flap that the flaps will not break or pull apart, and the bag closure, including two such flaps, is heavy and lacks flexibility. Various forms of closure have been suggested in an effort to overcome this objectionable feature but these have, for the most part at least, either lacked the necessary strength or they were difficult to make.

Bags of this type are usually closed at both ends when the bag is formed and the closure at one end of the bag is provided with a valve to permit the insertion of a filling spout and which may be closed after the bag has been removed from the spout. Such a valve is usually formed by leaving one of the end flaps of the closure free from the other flaps so that it may be moved into and out of engagement therewith. In the usual bag of this type such a valve does not close automatically when the bag is removed from the spout but it is necessary for the operator to drop the filled bag on its lower end or otherwise manipulate the same to cause the contents and air within the bag to force the valve upwardly to its seat. Even when the valve is properly closed very fine or powdered materials will sift about the same and escape from the bag in an objectionable manner. Further, the ordinary pasted bag of this type is not symmetrical or of equal thickness throughout its area and it is difficult to stack the filled bags in a vertical pile, or to stand individual bags on end or an edge, and inasmuch as the walls are not all flat some of them

will not properly display advertising matter printed thereon. As a result the use of paper bags for packing certain commodities has been, to a considerable extent, supplanted by the more expensive card board containers or boxes, this being particularly true in the case of commodities packed in small quantities and displayed on shelves and the like.

One object of the present invention is to provide a pasted end closure for a multi-ply bag which will combine flexibility with strength.

A further object of the invention is to provide a multi-ply bag with end flaps which are so constructed as to materially reduce the number of plies of paper and the number of layers of paste therein.

A further object of the invention is to provide such a bag which will be symmetrical in shape and of substantially uniform thickness throughout its area.

Other objects of the invention will appear as the bag is described in detail.

In the accompanying drawings Fig. 1 is a perspective view of a bag embodying my invention, showing the same fully extended; Fig. 2 is a plan view of the end closure with the end flaps folded inwardly; Fig. 3 is a similar view with one of the side flaps folded upon the end flaps; Fig. 4 is a plan view of the closure in its completed form; Fig. 5 is a perspective view of the end portion of a bag with the several plies separated to show the construction thereof; Fig. 6 is a detail view of a portion of one of the intermediate plies of a side flap; Fig. 7 is a similar view of a slightly modified form of intermediate ply; Fig. 8 is a similar view of another modified form of intermediate ply; Fig. 9 is a sectional view taken through the valve on a line 9—9 of Fig. 10; and Fig. 10 is a perspective view of the valved corner of the bag, showing a seal applied thereto.

In these drawings I have illustrated one embodiment of my invention, with certain modifications thereof, and have shown the same as applied to bags having multi-ply walls, but it will be understood that this particular embodiment has been chosen for the purpose of illustration only and that the invention may take various forms and may be applied to bags differing in detail from the bag here illustrated; and that some features of the invention are applicable to bags having single-ply walls. Further, I wish it to be understood that the term "paper" as herein used is intended to include any material capable of being folded and pasted in the manner described, and that the term "bag" is intended

to include any receptacle of the general type illustrated. The side walls of the bag may be stiff enough to be self-supporting and still have end portions sufficiently flexible to form flaps.

5. The invention, either as a whole or in part, may be applied to bags for packing various commodities in various quantities, and ranging in size from very small bags adapted to be displayed on the shelves of a store to large shipping bags.
10. The particular bag here illustrated is a shipping bag of the shallow type commonly used for packing cement and the like, its width being much greater than its thickness, and when extended it is rectangular in cross section, as shown in Fig. 1. The bag is of the multi-ply type and its walls may include any desired number of plies but, as here shown, the bag consists of five nested tubes and therefore each wall of the bag is made up of five plies of paper, as indicated in Fig. 5 by the reference numerals 11, 12, 13, 14 and 15. The several tube sections or plies are of the same length and the narrow or edge walls 16 of the bag are folded inwardly along a longitudinal line, 17, to provide each end wall with an inwardly folded longitudinal plait or gusset, by means of which the tubular body may be collapsed with the side walls 18 thereof in contact one with the other. To close the end of the bag the end portions 19 and 19a of the edge walls 16 are extended and folded inwardly along lines 20 to form the end flaps of the closure and in thus folding the end portions of the edge walls the adjacent portions of the side walls, to which the end flaps are connected, are also folded inwardly along the diagonal lines 21, as shown in Fig. 2. The end portions 22 and 23 of the side walls 18, which constitute the side flaps, are then folded inwardly successively, the side flap 22, as shown in Fig. 3, being first folded upon the end flaps 19 and 19a and the side flap 23 being then folded upon the side flap 22, as shown in Fig. 4. The side flap 22 is pasted to one or both of the end flaps and the side flap 23 is pasted to the flap 22, the paste having been applied to the flaps before the side flaps were folded inwardly. If the end closure is to be provided with a valve one of the end flaps, in the present instance the end flap 19, is not pasted but is left free from the side flaps so that it can be moved away from these flaps to receive the filling spout.
50. In order to avoid the stiff heavy flaps which result from pasting the several plies of each flap one to the other I have so constructed the flap as to materially reduce its thickness and thus provide the same with a relatively great degree of flexibility without objectionably decreasing its strength. For this purpose two or more of the plies of each side flap are of different widths at different points in their length, the wide portion of one being arranged adjacent to the narrow portion of another ply so that the wide portions of the two plies may lie in substantially the same plane and these wide portions of the plies are then pasted to another ply which is of substantially uniform width throughout its length. The exact form and arrangement of the plies may be varied and will depend in part upon the number of plies included in the flap. In the particular form here illustrated, in which each of the side flaps consists of five plies, the outer ply 11 and the inner ply 15 of each of the side flaps are of substantially uniform width throughout their length and their outer edges are substantially continuous. The intermediate plies 12, 13 and 14 have their outer or edge portions cut away
- at intervals to provide serrations or tongues 24, the outer ends of which terminate adjacent to the outer edges of the plies 11 and 15. The outer end portions of the tongues on each ply are spaced one from the other distances sufficient to receive between them the outer end portions of adjacent tongues on each of the other two plies. Preferably the tongues are of uniform shape and width and the adjacent tongues of each ply have their outer end portions spaced apart a distance equal to or slightly greater than twice their width. The tongues on each ply are arranged in staggered relation to the tongues on the other plies, so that the end portions of adjacent tongues on the plies 12 and 13 will lie in the space between the end portions of tongues on the ply 14. Preferably the end portions of the several plies are such that their lateral edges will lie close one to the other but it is not essential that they should be in contact and a short space between these edges or a slight overlapping of the edges will not materially modify the characteristics of the flap. The tongues on the several intermediate flaps are then pasted to both the inner flap 15 and the outer flap 11, the arrangement being such that each tongue will be pasted to both the inner and outer flaps but inasmuch as the end portions of the tongues are arranged in substantially the same plane it will be apparent that the edge portion of the pasted flap comprises only three thicknesses of paper and two layers of paste, whereas if the five plies of the flap had been of equal width throughout the flap would have consisted of five thicknesses of paper and four layers of paste.
110. The tongues or serrations on the intermediate plies may be of any suitable form and in Figs. 5 and 6 I have shown each tongue as being of a relatively great width at its rear end, that is, at its point of connection with the body of the flap, and the lateral edges of the tongue converge outwardly to the edge of the flap, the arrangement being such as to provide narrow V-shaped spaces between adjacent tongues. In Fig. 7 I have shown the tongues of slightly different shape. 115 In this form also the rear portion of each tongue, as shown at 25, is of relatively great width and its edges converge outwardly but the outer or edge portion of the tongue, 26, has its lateral edges substantially parallel so as to provide relatively 120 large portions of the tongues lying in the same plane. In Fig. 8 I have shown the tongues, 27, substantially similar to those shown in Fig. 6 with the exception that the lateral edges thereof are curved instead of straight, the edges of the several 125 plies being scalloped.
130. When the end closure is provided with a valve, as shown at 19, the valve flap is connected at its lateral edges with the inwardly folded portions of the side flaps, which flaps are connected with the side walls 18, (Fig. 9) and is connected at its outer edge with the adjacent edge wall 16. That portion of the plaited edge wall adjacent to the flap is creased along the lines 28 which converge from the corners of the valve to the apex of the 135 plait in the edge wall and the outer edge of the valve is thus connected with the edge wall by a triangular section of that wall which, when the bag is collapsed, is folded inwardly parallel with the valve flap, the closure as a whole being folded 140 on a line 29 to a position parallel with the side walls. When the bag is opened and extended the movement of the inwardly folded plait in the edge wall to its extended position will carry the triangular section outwardly into substantially 145 150

the plane of the edge wall and will thus cause the valve flap to be moved outwardly to its closed position, that is, in contact with the inner side flap. This automatic closing of the valve has 5 two important results, it causes the valve to be automatically and instantly closed when the bag is removed from the filling spout, without the necessity of dropping the bag or otherwise manipulating the same to cause the valve to be 10 closed by the material within the same. Further, it permits the bag to be provided with a valve in each end closure so that either end of the bag which is picked up by the operator may be applied to the filling spout. This cannot be done 15 with the ordinary valved bag because the valve does not close automatically and if such a valve were provided in the lower end closure of the bag the material deposited on the center of the closure by the spout would find its way beneath the valve 20 flap before sufficient material had been deposited on the valve flap itself to close the same, and consequently the valve would not be closed. With the present bag the opening or extending of the bag closes the valve and when a valve is provided 25 in the lower end closure no material can enter beneath the same but the valve will remain closed and eventually the material piled thereon will firmly hold it in a closed position.

When the bag is extended the plaited edge 30 walls move outwardly into positions in which they are substantially flat and perpendicular to both the side walls and the closures, the triangular section, which connects the one edge wall with its valve, moving with the edge wall into 35 the same plane therewith. Consequently that portion of the edge wall with which the valve flap 19 is connected is flat and smooth, thereby permitting a seal to be applied thereto by pasting, as by pasting a strip of paper 30 on the closure and on the end of the adjacent edge wall 40 so that it will extend over the valve flap and completely close the valve opening and thus prevent any sifting of fine material about the valve. This cannot be done with the ordinary valve bag 45 because the edge walls are folded outwardly and when the bag is extended they do not assume flat or perpendicular positions but are more or less bowed, and the end portions, which are connected with the valve, are sloping and irregular so 50 that it is not practical to paste a seal on the same. Further, this characteristic of the edge walls results in the production of a bag which, when filled, is of symmetrical form and of uniform thickness throughout its area so that the filled 55 bags may be stacked one upon the other in a firm vertical pile. The edge walls, as well as the end and side walls, of the filled bag being substantially flat, the individual bags will stand alone on any wall that may be placed lowermost, 60 and all the walls are well adapted to display advertising matter printed thereon.

While I have shown and described one embodiment of my invention, together with certain modifications thereof, I wish it to be understood that 65 I do not desire to be limited to the details thereof as various modifications may occur to a person skilled in the art.

Having now fully described my invention, what I claim as new and desire to secure by Letters 70 Patent, is:

1. A bag comprising multi-ply walls having at their ends flaps which are folded inwardly to form an end closure, one of said flaps having a ply provided with a continuous edge and having other plies provided with serrated edges, the serrations

of the several plies being arranged in staggered relation and being pasted to the continuous edge of the first mentioned ply, said flap as a whole being pasted to an adjacent flap.

2. A bag comprising multi-ply walls having 80 at their ends flaps which are folded inwardly to form an end closure, one of said flaps having inner and outer plies provided with continuous edges and also having a plurality of intermediate plies each of which is provided with a series of tongues spaced one from the other, the tongues on said intermediate plies being arranged in staggered relation and being pasted to both the inner ply and the outer ply and said inner ply being pasted to an adjacent flap.

3. A bag comprising multi-ply walls having 85 at their ends flaps which are folded inwardly to form an end closure, one of said flaps having a ply provided with a continuous edge and having a plurality of other plies each provided with a series of spaced tongues, the lateral edges of which converge toward the outer edge of said flap, the narrow portion of each tongue being arranged between narrow portions of adjacent tongues on another ply and all of said tongues 90 being pasted to the first mentioned ply and said flap as a whole being pasted to an adjacent flap.

4. A bag comprising multi-ply walls having 100 at their ends flaps which are folded inwardly to form an end closure, one of said flaps having a ply provided with a continuous edge and having a plurality of other plies each provided with a series of spaced tongues, the lateral edges of which converge toward the outer edge of said flap, the narrow portion of each tongue being 105 arranged between narrow portions of adjacent tongues on another ply and the wider portion of each tongue overlapping said adjacent tongues on said other ply and all of said tongues being pasted to the first mentioned ply and the flap 110 as a whole being pasted to an adjacent flap.

5. A bag comprising multi-ply walls having 115 at their ends flaps which are folded inwardly to form an end closure, one of said flaps having inner and outer plies provided with continuous 120 edges and also having a plurality of intermediate plies each of which is provided with a series of tongues the lateral edges of which converge toward the edge of said flap and the narrow portion of each tongue on each intermediate flap 125 being arranged between the narrow portions of adjacent tongues on another intermediate flap and all of said tongues being pasted to said inner and outer plies and said inner ply being pasted to an adjacent flap.

6. A bag comprising multi-ply walls having 130 at their ends flaps which are folded inwardly to form an end closure, one of said flaps having a ply provided with a continuous edge and having a plurality of other plies each provided with a 135 series of spaced tongues, the tongues on each ply being so arranged with relation to the tongues on the other plies that the outer end portions of the tongues on two of said plies will lie edge to edge between the outer end portions of adjacent tongues on a third ply, the tongues of each ply being pasted to the first mentioned ply and the flap as a whole being pasted to an adjacent ply.

7. A bag comprising multi-ply walls having 140 at their ends flaps which are folded inwardly to form an end closure, one of said flaps having inner and outer plies provided with continuous edges and also having a plurality of intermediate plies each of which is provided with a series of tongues spaced one from the other, the tongues

of each intermediate ply being so arranged with relation to the tongues on the other intermediate plies that the outer end portions of the tongues on two of said plies will lie edge to edge between the outer end portions of adjacent tongues on the third ply, the tongues of each ply being pasted to both said inner ply and said outer ply and said inner ply being pasted to an adjacent flap.

8. A bag having walls the end portions of which 10 constitute flaps adapted to be folded inwardly to form an end closure, each flap comprising a plurality of plies and one of said flaps having a ply of substantially uniform width throughout its length and having a plurality of other plies each 15 having alternate portions of unequal width, a wider portion of one of the last mentioned plies being arranged adjacent to a narrow portion of another of said last mentioned plies, whereby the outer edge portions of said last mentioned plies 20 will lie in substantially the same plane, all the last mentioned plies being pasted to the first mentioned p'y and the flap as a whole being pasted to an adjacent flap.

9. A bag having walls the end portions of which 25 constitute flaps adapted to be folded inwardly to form an end closure, one of said flaps comprising inner and outer plies which are of substantially uniform width throughout its length, a plurality of intermediate plies each having alternate portions of unequal width, the wide and 30 narrow portions of adjacent intermediate plies being so arranged with relation one to the other that the outer edge portions of the several intermediate plies will lie in substantially the same plane, the several intermediate plies being pasted to both said inner ply and said outer ply and said 35 flap as a whole being pasted to an adjacent ply.

10. A closure for a multi-ply bag comprising

end flaps adapted to be folded inwardly and side flaps adapted to be folded one on the other end on said end flaps, each of said side flaps comprising inner and outer plies each of substantially uniform width throughout its length, and a plurality of intermediate plies each having alternate portions of unequal width, the wide and narrow portions of adjacent intermediate plies being so arranged with relation one to the other that the outer edge portions of the several intermediate plies may lie in substantially the same plane, the several intermediate plies being pasted to both said inner ply and said outer ply and the inner ply of one of said side flaps being pasted to the outer ply of the other side flap.

11. A bag comprising side walls provided at their adjacent ends with multi-ply flaps adapted to be folded inwardly to form an end closure, the inner and outer plies of one of said flaps being of substantially equal width and having continuous edges, and an intermediate ply of said flap having alternate portions of unequal width spaced apart lengthwise thereof and pasted to said inner and outer plies, and one of the first mentioned plies being pasted to an adjacent flap.

12. A bag comprising side walls provided at their adjacent ends with multi-ply flaps adapted to be folded inwardly to form an end closure, the inner and outer plies of one of said flaps being of substantially equal width and having continuous edges, and an intermediate ply of said flap having tongues spaced apart lengthwise thereof, the ends of said tongues being adjacent to the edges of said inner and outer plies and pasted thereto, and one of the first mentioned plies being pasted to an adjacent flap.
